UNITED STATES PATENT OFFICE.

ERNEST C. THORSCHMIDT, OF NEW YORK, N. Y.

MACHINE FOR APPLYING BILGE-HOOPS TO CASKS AND BARRELS.

No. 850,692.

Specification of Letters Patent.

Patented April 16, 1907.

Application filed February 17, 1906. Serial No. 301,532.

To all whom it may concern:

Be it known that I, ERNEST C. THORSCHMIDT, a citizen of the United States, residing at the borough of Brooklyn, in the county of Kings, city and State of New York, have invented an Improvement in Machines for Applying Bilge-Hoops to Casks and Barrels, of which the following is a specification.

My invention relates to a machine for applying bilge-hoops to casks and barrels, and particularly to the apparatus employed in such machines for forcing the bilge-hoop to place on the casks and barrels, and it is an improvement on the apparatus heretofore employed by me for this purpose and shown and described in Letters Patent No. 753,014, granted to me February 23, 1904, for an improvement in machines for applying bilge-hoops to casks and barrels.

Heretofore, due to the inadjustability of the outwardly-yielding devices or dogs employed to force the hoops to place in machines of the class to which the present invention relates, it has been necessary to construct and employ different-sized machines for applying hoops to different-sized barrels, each sized barrel requiring a machine of special proportions to apply the hoops thereto; and the object of my present invention is to provide an apparatus in which the dogs employed to force the hoops to place are adjustable radially within certain defined limits, whereby a given machine is adapted for use in applying hoops to different-sized barrels.

In carrying out my invention I employ a cage or annulus member, a plunger connected thereto and by which the same may be actuated, annular plates secured to and forming part of the said cage member, a series of outwardly-yielding devices arranged in groups between the said annular plates, means for adjusting the said yielding devices radially, and means for securing the said yielding devices in predetermined positions between the said annular plates, all of which will be hereinafter more particularly described.

In the drawings, Figure 1 is a partial plan and cross-section of the annulus or cage member. Fig. 2 is an elevation and partial section of the same. Fig. 3 is an enlarged section on line $x-x$, Fig. 1. Fig. 4 is an enlarged section on line $y-y$, Fig. 1. Fig. 5 is an

inverted plan of the cap member forming part of the adjustable frame employed between the annular plates. Fig. 6 is a section on line $z-z$, Fig. 5. Fig. 7 is a plan of the base member of the frame employed between the annular plates. Fig. 8 is a side elevation of the adjustable frame, showing the parts thereof in relation to one another. Fig. 9 is a cross-section on line $1-1$, Fig. 7, looking to the left. Fig. 10 is a cross-section on line $2-2$, Fig. 7, looking to the right. Fig. 11 is a cross-section on line $y'-y'$, Fig. 7. Fig. 12 is a cross-section on line $z'-z'$, Fig. 7; and Fig. 13 is a cross-section on line $x'-x'$, Fig. 7.

Referring to the drawings, a designates an annular plate which is secured in a suitable manner to a series of radially-placed arms 3 , terminating in a hub 4 , in which is suitably secured a plunger 5 .

b is an annular plate preferably of the same dimensions as the annular plate a , and in equally-spaced-apart positions these annular plates may be provided with holes to receive the bolts $b'-b'$, by which the same may be secured together. Between the annular plates a and b , and preferably between each pair of bolts $b'-b'$, I employ a series of radially-adjustable frames c , each frame c comprising a base member d and a cap member e , which are of corresponding dimensions and preferably sector-shaped. On the inner surface of the cap member e in suitable positions I employ lugs 6 , and adjacent to the edges thereof this cap member e is provided in suitable positions with pin-holes 7 .

The base member d of each of the frames c is provided with outer walls $f-f'$ and a central wall g . The middle portion of the central wall g is preferably cut away, providing a lug 8 at the outer end thereof and a lug 9 at the inner end thereof. Midway between the central wall g and the outer walls $f-f'$ there are radial ribs $h-h'$, and adjacent to and parallel with the walls $f-f'$ there are extending ribs $10-11$, respectively. The sides of the rib h are parallel, respectively, with the sides of the rib 10 and the adjacent side of the wall g , and similarly the sides of the rib h' are parallel with the side of the rib 11 and the opposite side of the wall g , whereby between these ribs are parallel-sided ways 12 , each of which is radially disposed and adapted to receive one of the yielding dogs i . Each of

these dogs is preferably square in cross-section, in order that when one working surface of the same is worn it may be turned and another surface employed, and also each 5 surface of each dog is provided with recesses 13 and the inner end thereof with a circular recess 14.

In correspondingly opposite positions the 10 sides of the ribs h and 10, ribs h' 11, the rib h , and the wall g and the rib h' and the opposite side of the wall g are provided with notches adapted to receive the opposite ends of suitable stop-bars l , which when the dogs i are in 15 position are received within the recess 13 in the under surface of the same, and manifestly not only limit the outward but also the inward movement of the said dogs. The outer walls f, f' of the base member d are provided with holes f^2 in positions corresponding 20 with the holes 7 provided in the cap member e , and when the cap member is superimposed on the base member to form the frame c the parts thereof may be held in position by means of pins 15 passing through the holes 25 7 and cap member into the correspondingly-placed holes f^2 and in the walls f, f' of the base member, and, as indicated in Fig. 8, with the parts in this position the lugs 6 on the inner face of the cap member bear against 30 or are adjacent to the outer ends of the ribs h, h' , and the dogs are maintained in their normal positions by means of suitable springs m extending between the inner faces of the lugs 6 and into the circular recesses 14 in the 35 inner ends of the dogs.

In suitably-spaced-apart positions, preferably midway between the points at which the bolts b, b' are employed, the outer face of the annular plate a is provided with a series of 40 depending lugs n , each of which is provided with an opening adapted to receive a shouldered adjusting-screw o , which also passes through a screw-threaded opening 17 in the lug 8 on the base member d of each frame c 45 and bears against a block of hard wood 18 into a suitable recess in the central wall g of the base member d , the block of wood being employed to relieve the strain to which the adjusting-screw is subjected, and midway 50 between the pair of bolts b, b' the upper surface of the plate b is provided with radially-disposed recesses 19, each adapted to receive a tongue 20, secured centrally to the under surface of each base member d by screws 21 55 or otherwise and by which the movement of each of the frames c is limited to a radial one.

It will now be manifest that the frames c may be secured in predetermined positions between the annular plates a, b by means of 60 drawing up the nuts on the bolts b, b' , and also that by loosening the nuts on the bolts b, b' and by turning the adjusting-screws o the radial positions of the series of frames c ,

and consequently the dogs i , may be radially 65 adjusted within certain limits, and consequently the apparatus may be adjusted to apply the hoops to different-sized barrels, in the operation of which the hoop or hoops are placed over the assembled barrel-staves and the annulus or cage member brought down 70 thereon, the dogs engaging the edge of the hoop and with the continued movement of the annulus or cage member force the same to position, it being understood that the members d, e of the frame are so spaced 75 apart by the walls f, f' and the lugs 8 and 9 as to permit of the proper movement of the dogs when the frames are clamped between the annular plates.

I claim as my invention—

1. In a machine for applying bilge-hoops to barrels, the combination with annular plates, of means for securing the said annular plates together, a circularly-arranged series of outwardly-yielding devices between the 85 said annular plates and means for radially adjusting the positions of the said yielding devices.

2. In a machine for applying bilge-hoops to casks and barrels, the combination with 90 an annular plate, of a second annular plate, means for securing the said annular plates together, a circularly-arranged series of outwardly-yielding devices in groups between the said annular plates and means for radially 95 adjusting the position of each group of yielding devices.

3. In a machine for applying bilge-hoops to casks and barrels, the combination with an annular plate, of a second annular plate, 100 means for securing the said annular plates together, a series of frames between the said annular plates, a series of radially-placed outwardly-yielding devices in each of said frames and means for radially adjusting the 105 position of the said frames and yielding devices.

4. In a machine for applying bilge-hoops to casks and barrels, the combination with an annular plate, of a second annular plate, a 110 series of frames between the said annular plates, a series of radially-placed outwardly-yielding devices in each of said frames, means for radially adjusting the position of each of said frames and the yielding devices 115 therein and means for securing together the said annular plates with the said frames and yielding devices between them.

5. In a machine for applying bilge-hoops to casks and barrels, the combination with 120 an annular plate, of a second annular plate, a series of frames between the said annular plates, a series of radially-placed outwardly-yielding devices in each of said frames, means for moving the said frames, means for limiting the movement of each of said frames to 125

a radial direction and means for securing the said annular plates together with the said frames and the yielding devices between them.

5 6. In a machine for applying bilge-hoops to casks and barrels, the combination with an annular plate, of a second annular plate, a series of frames circularly arranged between the said plates, each of said frames comprising a base member and a cap member, means for securing the base and the cap member together, a series of radially-placed outwardly yielding devices within each of said frames, means for radially adjusting the positions of 10 the said frames and means for clamping the said annular plates together with the said frames between them.

15 7. In a machine for applying bilge-hoops to casks and barrels, the combination with an annular plate, of a second annular plate, a series of frames circularly arranged between the said plates, each of said frames comprising a base member and a cap member, a series of dogs, radial ways in the base member 20 to receive the said dogs, means for projecting the said dogs inwardly, means for limiting the projecting positions of the said dogs, means for radially adjusting the position of each of said frames and means for clamping the 25 annular plates together with the said frames between them.

30 8. In a machine for applying bilge-hoops to casks and barrels, the combination with an annular plate, of a second annular plate, having radially-disposed recesses in its upper 35 face, a series of frames circularly arranged between the said plates, each of said frames comprising a base member and a cap member, a series of dogs, radial ways in the base 40 member to receive the said dogs, means for projecting the said dogs inwardly, means for limiting the projected positions of the said dogs, means for radially adjusting the position of each of said frames, a tongue secured 45 to the base member of each of said frames and adapted to be received in one of the aforesaid recesses within the upper face of the second annular plate to cause the said frames in being adjusted to move in a radial 50 direction and means for securing the said annular plates together with said frames intervening.

55 9. In a machine for applying bilge-hoops to casks and barrels, the combination with an annular plate, of a second annular plate, a series of frames circularly arranged between the said plates, each of said frames comprising a base member and a cap member, dogs each provided with a circular re- 60 cess in one end thereof and recesses in similar positions in each face thereof, radial ways in the base member of each of said frames to receive the said dogs, stop-bars secured in

the said ways and adapted to be received in the said recesses in the faces of the said dogs 65 to limit the movement thereof, springs for normally projecting the said dogs inwardly, means for radially adjusting the said frames and means for securing the said annular plates together with the said frames intervening. 70

10 10. In a machine for applying bilge-hoops to casks and barrels, the combination with an annular plate, of a second annular plate, a series of frames circularly arranged between the said plates, each of said frames comprising a base member and a cap member, dogs each provided with a circular recess in one end thereof and recesses in similar positions in each face thereof, radial ways in the base 80 member of each of said frames to receive the said dogs, stop-bars secured in the said ways and adapted to be received in the said recesses in the faces of the said dogs to limit the movement thereof, springs for normally 85 projecting the said dogs inwardly, means for radially adjusting the said frames, a series of spaced-apart downwardly-projecting lugs on the outer surface of the upper annular plate, an adjusting-screw passing through each of 90 said downwardly-projecting lugs and into the base member of one of the said frames for adjusting the position of the same radially and a series of bolts passing through said annular plates to clamp the same together with the said frames intervening. 95

11. In a machine for applying bilge-hoops to barrels, the combination with an annular device to be brought down over the head of the barrel, of a circularly-arranged series of 100 outwardly-yielding devices which with the annular device occupy a common plane at right angles to the axis of the barrel, and said yielding devices arranged within said annular device and operating in the plane thereof 105 and means for radially adjusting the position of the said yielding devices.

12. In a machine for applying bilge-hoops to casks and barrels, the combination with an annular device adapted to be brought 110 down over the head of the barrel, of a circularly-arranged series of outwardly-yielding devices in a common plane and at right angles to the axis of the barrel and arranged in groups within said annular device and means 115 for radially adjusting the position of each group of said yielding devices.

13. In a machine for applying bilge-hoops to casks and barrels, the combination with an annular device adapted to be brought 120 down over the head of the barrel, of a series of frames within the said annular device, a series of radially-placed outwardly-yielding devices in each of said frames and means for radially adjusting the position of the said 125 frames and yielding devices.

14. In a machine for applying bilge-hoops to casks and barrels, the combination with an annular device adapted to be brought down over the head of the barrel, of a series of frames within the said annular device, a series of radially-placed outwardly-yielding devices in each of said frames, means for moving the said frames and means for limit-

ing the movement of each of said frames to a radial direction.

Signed by me this 8th day of February, 1906.

ERNEST C. THORSCHMIDT.
